J. HARRISON.
Mode of Ringing Bells.

No. 41,843.

Patented March 8, 1864.

Inventor:
James Harrison

UNITED STATES PATENT OFFICE.

JAMES HARRISON, OF NEW YORK, N. Y.

IMPROVED MODE OF RINGING BELLS.

Specification forming part of Letters Patent No. 41,843, dated March 8, 1864.

To all whom it may concern:

Be it known that I, JAMES HARRISON, of the city of New York, in the county of New York and State of New York, have invented a new and useful Improvement in Ringing Bells; and I do hereby declare that the following is a full, clear, and exact description of the construction and operation of the same, reference being had to the annexed drawings, making a part of this specification, in which—

Figure 1 is a perspective view of the bell and mountings complete. Fig. 2 is a perspective view of the mountings for the bell, partially disconnected in order to show some parts that cannot be seen in Fig. 1. Figs. 3 and 4 are transverse sections. Figs. 5 and 6 are perspective sections; Fig. 7, an inside view of cap G; Fig. 8, an outside top view of gear-wheel C.

To enable others skilled in the art to make and use my invention, I will now describe its construction and operation.

The word "bell" represents the bell; letter A, the yoke; letters B B, the arms or journals; letter C, the gear-wheel bolted on top of the bell; letter G, the cap that covers nut F; letter H, a check-nut; letter I, the bolt on which the bell is made to turn; J, the ratchet-wheel that works the worm or screw K into gear-wheel C. Letter L is a check-dog to prevent ratchet-wheel J from moving backward. Letters M and N are the working lever and pawl that work into ratchet-wheel J; letter O, a friction-roller on the end of lever M; letter P, a cam bolted onto standard T T at v v. The springs S S S are applied to lever M, pawl N, and check-dog L to keep them in their places; U, the rope-wheel; W, the clapper; Z, the wood frame.

As the bell is moved to and fro in the action of ringing, the roller O on lever M is moved up and down cam P. As it comes down it moves the working-pawl N into a fresh tooth on ratchet-wheel J, and as it goes up again it moves the ratchet-wheel J forward one tooth, and the check-dog L drops into it and keeps it there, and so it continues to move the distance of one tooth on the ratchet-wheel J at every blow of the hammer or clapper. The screw or worm K is fastened on the same pin with ratchet-wheel J and working into gear-wheel C to which the bell is made fast, so that in moving round the ratchet-wheel J you move

the screw or worm K, and by that the gear-wheel C, and as the bell is bolted fast to gear-wheel C as a matter of course it moves with it. In this way the bell is made to rotate around the clapper or hammer horizontally by the action of ringing the bell. Bolt I is the principal bolt that bears the weight of the bell, and the two washers thereon (marked a a') is the point of friction on which the bell turns. The gear-wheel C, as shown in Fig. 2, has a hub, D, and shank, E, made to fit a corresponding hole in yoke A, making a perfect right-angle joint at D, and bolt-holes made to suit the top of the bell, as shown in Fig. 8, and marked 1 2 3 4 5. The bolt I is put through the top of the bell first and then through gear-wheel C, hub D, and shank E and yoke A to receive nut F, which is screwed up until the bell is fast.

Letter G is a cap with a hole in center to fit nut F, and slots in the outer edge, as shown in Fig. 7 and marked g g g g, made to fit lugs v v on the top of yoke A. This is to prevent the clapper from moving round with the bell.

Letter H is a check-nut, which goes on cap G to keep the bell firmly in its place. Fig. 3 shows the position of ratchet-wheel J, check-dog L, and spring S, working on the outside, and screw or worm K inside the ears A' on yoke A.

Fig. 4 shows part of yoke A, with lever M working through the arm of yoke A, instead of working on the outside, as shown in Figs. 1 and 2; also, the worm or screw K, ratchet-wheel J, and check-dog L inside the ears A' on yoke A.

Fig. 5 shows the same as Fig. 4, with the addition of gear-wheel C' and an intermediate gear-wheel, C'', for the purpose of connecting gear-wheel C' with screw or worm K.

Fig. 6 is to show the use of a concave cam, P, fastened to standard T T and an upright lever, M, with friction-roller O working from arm B on yoke A.

The object of this invention is the use of new and original mechanical devices as applied to the ringing and rotating of a bell at one and the same time by the action of ringing or sounding the bell. The value of these devices or improvements is, first, that it reduces the cost of mounting the bell one-third the original cost; second, it is more simple and much easier to operate, and less liable to

get out of order than any device ever invented for the same purpose.

What I claim as my invention, and wish to secure by Letters Patent, is—

1. 'The combination of the gear-wheel C with the hub D and shank E fitted to a corresponding hole in yoke A, making a perfect right-angle joint at the point D, and the bolt-holes 1 2 3 4 5, for the purpose of fastening the wheel to the bell, as specified.

2. The combination of levers M with the working-pawl N and check-dog L, ratchet-wheel J and screw or worm K, and cam P

with friction-roller O, for the purpose specified.

3. The combination of cap G, with hole in center to fit nut F that bears the weight of the bell, and slots *g g g g* to fit lugs *v v* on yoke A, substantially as specified.

4. The working of lever M through the arm of yoke A and the ears A' on yoke A, substantially as described.

JAMES HARRISON.
